UNITED STATES PATENT OFFICE

FLORICEL A. STAPLER, OF PHILADELPHIA, PENNSYLVANIA, ASSIGNOR TO VICTOR
TALKING MACHINE COMPANY, A CORPORATION OF NEW JERSEY

MEMBER OR STRUCTURE VIBRATED BY ENERGY IMPULSES

Application filed October 10, 1928, Serial No. 312,911. Renewed January 6, 1931.

My invention relates to a member or structure partaking of vibratory motion under the influence of energy impulses having a frequency, usually, varying between 16 and 5 20,000 cycles per second or those having a frequency of the order usually encountered in speech or music transmission.

My invention relates to a member or structure, as aforesaid, utilized to transmit or 10 transfer energy impulses, as aforesaid, from one region to another or from a transmitting member to a receiving member.

My invention relates to a member or structure, as aforesaid, as an arm or bar to which 15 vibratory motion is imparted by a transmitting member or system, as a phonograph record or a magnetic structure, the energy impulses actuating or controlling a suitable receiving member or system, as a diaphragm, 20 armature, or the flux in a magnetic circuit.

In accordance with my invention, a member or structure, as aforesaid comprises a single element or part including a web section from which projects spaced wing hinges 25 and a hinge connecting neck.

Further in accordance with my invention, the aforesaid member or structure comprises a single element or part having spaced walls connected by a transverse wall, the aforesaid 30 web section being disposed in the plane of said transverse wall and the aforesaid wing hinges and hinge connecting neck being disposed substantially at right angles to said web section.

35 Further in accordance with my invention, a flange is formed on a chambered element or part, as aforesaid, transversely of the longitudinal axis thereof, and said flange is received by a slot or channel provided in a member, one end of which is disposed within 40 said element or part.

In accordance with one important phase of my invention, the aforesaid member or structure is an arm or bar carrying, at one end, a 45 stylus or needle, the other end thereof being connected to a sound-producing diaphragm. The detailed description following hereafter refers to a construction of the character last described, although it shall be understood 50 that my invention is not to be thus limited,

My invention resides in the member or structure, article, method and features of construction of the character hereinafter described and claimed.

For an illustration of some of the forms 55 my novel member or structure, or article may take and for an understanding of my method, reference is to be had to the accompanying drawings in which:

Figure 1 is a perspective view, partly 60 broken away, of separate parts of a needle arm or stylus bar constructed in accordance with my invention.

Fig. 2 is a vertical sectional view, partly 65 in elevation, of the structures shown in Fig. 1.

Fig. 3 is a vertical sectional view, partly 70 in elevation, of the structures illustrated in Fig. 2 after they have been assembled.

Fig. 4 is a vertical sectional view, partly 75 in elevation, of my novel needle arm or stylus bar and associated parts of a sound box.

Fig. 5 is a front elevational view of a part 80 of the sound box illustrated in Fig. 4.

For purposes of explanation, my invention is illustrated and described in connection 75 with a member or structure, such as a needle arm or stylus bar, of the character disclosed in the co-pending Mallina application, Serial No. 311,487, filed Oct. 10, 1928.

As particularly described in the aforesaid 80 application, a suitable blank or stamping of sheet material is brought, by a series of shaping operations, to the configuration of the member A, Fig. 1. As illustrated in Fig. 1, member A comprises a hollow, circumferentially complete body portion formed by side walls a, a, a top wall b and a bottom wall c, the latter comprising flanges, soldered or otherwise suitably secured together, said flanges, previous to the shaping operation, 85 constituting the outer edges of the blank or stamping. Forming an extension of one end of the wall b is a member d while from the other end of said wall b and extending beyond each side thereof is a web section e disposed in the plane of the said wall b.

Disposed at right angles or substantially so, in the example shown, to the web section 90 e are the spaced wing or pivot hinges f, f. In accordance with my invention, said wing 100

hinges f, f are connected by a neck or flange g disposed in a plane common to said wing hinges f, f and positioned at right angles, or substantially so, to the web section e .

5 The aforesaid member A , at one end thereof, as hereinafter more particularly described, is connected to a diaphragm, or equivalent, by the member d . The other end of member A is secured or attached to a talking-machine-stylus-retaining-member B , or equivalent, which, in the example illustrated, and as more particularly described in the aforesaid Mal-lina application is generally rectangular in configuration and comprises a solid body of metal formed, preferably, by a stamping operation. The upper surface of member B as illustrated in Figs. 1, 2 and 3 comprises a lug or extension h and, in accordance with my invention, a crosswise slot i which, among others has the function of locating the position at which member B is secured to member A . The bottom surface of member B comprises a shouldered portion j , the rear surface thereof, preferably, being inclined as indicated at k . Disposed axially of the member B and extending a suitable distance thereinto is a passage or opening for the reception of a talking machine needle or stylus m , Fig. 4, retained in the position illustrated by the 15 shank of a clamping screw n threaded into a passage opening into the aforesaid passage substantially at right angles with respect thereto and passing through the lug h .

In accordance with my invention and to 35 the end that the aforesaid members A and B may be assembled, web section e , neck g and hinge wings f, f are bent into the position illustrated by the broken lines in Fig. 2. Thereafter, the sloping and shouldered end 40 of the member B is passed from right to left, Fig. 2, into the open end of the chamber formed by the walls a, a, b , and c until the shouldered portion j engages with the adjacent end of the bottom wall c . Thereupon, 45 the web section e , flange g and hinge wings f, f are restored to substantially their original position, to wit, the position illustrated by the full lines in Fig. 2. In so doing, the central portion of the neck or flange g is 50 passed into the slot i of member B . Thus assembled, it is desirable that all adjacent or contacting surfaces be soldered together.

A needle arm or stylus bar of the character hereinbefore described is illustrated in Fig. 4 as forming part of a talking machine or phonograph sound box. This sound box may be of any suitable character and in Fig. 4 is shown as comprising a base section 1 terminating in a tubular conduit 1 a adapted to 55 be associated with the tone arm of a sound amplifying horn. A diaphragm 2 of any suitable character, which, however, in the example illustrated, is of the type illustrated in my co-pending application, Serial No. 65 311,553, filed Oct. 10, 1928, is received at its

peripheral edge between washers 3, 3, a cap member 4 cooperating with a ring 5 threaded thereto to retain the diaphragm 2 in the position illustrated. One side of the cap member 4 may be skeleton-like by virtue of which one side of the diaphragm 2 is placed in direct communication, through a plurality of passages, with the surrounding atmospheric medium. At the side of the diaphragm 2 facing the conduit 1 a there may be disposed a plug or member 6 for producing properly dimensioned paths for the propagated sound waves.

In the example illustrated, the needle arm or stylus bar is secured to the diaphragm 2 only at the midpoint thereof, the member d constituting a tie member between the needle arm proper and the diaphragm, said member d , in the example shown, passing through a bushing disposed centrally of the diaphragm and being suitably secured thereto as by a mass of wax or solder, not shown.

The wings f, f constitute the hinging or pivotal support for the needle arm or stylus bar and they may be supported in any suitable manner. To this end, in the example shown, the cap section 4 is provided with the lugs or members 7 projecting laterally therefrom, each of the aforesaid wings f, f being received between one face of a lug 7 and a plate or member 8. In the example shown, each wing f is provided, during the stamping operation, with a passage $f1$, through each of which and aligned passages in a lug 7 and member 8, extends a bolt 9 for clamping the wings and for pivotally mounting the needle arm in the position illustrated in Fig. 4. In this manner, the needle arm may be mounted for hinging or pivotal movement and, due to the fact that the wings f, f are constructed of resilient material, said needle arm is self-restoring in the sense that, of its own volition, it tends to return to an original position after being moved from such position.

Energy impulses set up by the phonograph or talking machine record are transmitted to the sound producing diaphragm by the thereto-connected needle arm or stylus bar. It is highly desirable, therefore, that the latter be so constructed as to be freely vibratable in one plane, readily restorable to an original position, and resistant to vibration in planes other than said one plane. A needle arm constructed and mounted as hereinbefore described and illustrated is readily movable or vibratable only in the forward and reverse direction in which it moves when moving the diaphragm 2 or the central portion thereof side-wise in either direction. In other words, if the parts were positioned as illustrated in Fig. 4, the needle arm would be readily vibratable in the plane of paper, the pivotal or hinging axis of said needle arm being dis-

posed in those portions of the wings f, f beyond the lugs 7.

At the same time, due to the construction and arrangement of parts, the needle arm is 5 not freely vibratable or movable in a direction longitudinally thereof, nor in that direction in which it would move under the influence of friction imposed by the record which, were the parts positioned as illustrated in Fig. 4, would be substantially at right angles to the plane of the paper. The non-vibratory or non-movable features of the needle arm noted immediately above arise primarily due to the provision of the web section e which remains in the original plane of the wall b . This web section e and neck g connect the wings f, f and constitute a structural angle section which effectively impedes and substantially prevents needle arm movement 10 longitudinally thereof and in the direction imposed by record friction, as aforesaid. Moreover, said web section e and the connecting neck g , in effect, form a truss or support which braces the wings f, f and the shaped 15 body portion of the member A.

A needle arm or stylus bar constructed and mounted in accordance with my invention, besides possessing the desirable pivotal or hinging characteristic noted above, is of minimum weight, particularly the material from 20 which the member A was formed, which may be elastic or resilient in character, as steel or bronze having a thickness of the order of 0.008 of an inch, more or less. Due to this 25 feature, the moment of inertia about the needle arm pivotal or hinging axis is small and, as a result, the quality of sound production is improved.

It is highly desirable that the connecting 30 tie member d be formed integrally with the needle arm proper and this may readily be accomplished by forming the part d by the same die structure that forms the blank from which the member A is formed. Moreover, 35 since the material forming the member A is very thin, it follows that the mass of the tie member d is kept small, this being highly desirable.

The tie member d may lead direct to the 40 diaphragm or, preferably and as illustrated, the connection may be circuitous and comprise a U-shaped bend d_1 , or equivalent, by virtue of which the flexibility of the tie connection is improved. It should also be noted 45 that there is a portion d_2 of the tie member d beyond the hollow, circumferentially complete body portion of member A. This portion d_2 of the tie member is substantially in alinement with wall b and, during a period of 50 sound production, flexing or giving action in the needle arm proper largely occurs in said portion d_2 .

Although the aforesaid members, structure, bars or arms have been illustrated and 55 described as operated by a phonograph or

talking machine record, it shall be understood that my invention is not to be thus limited. Thus, for example, said members, structure, bars or arms may be magnetically actuated, the needle or stylus, in such case, 70 being omitted.

Although the hereinbefore described members, structures, bars or arms have been specifically referred to for diaphragm-actuating purposes, it shall be distinctly understood that my invention is not to be limited to 75 such an arrangement.

Thus, for example, said members, structures, bars or arms, actuated or vibrated by a stylus or needle, or otherwise as desirable, 80 may be utilized to transfer impulse energy to the vibrating element or to serve as the vibrating element of any vibrating device for which they are adapted, particularly devices vibrating in accordance with sound. 85

What I claim is:

1. A vibratable member for transmitting energy impulses from one region to another, said member comprising a single member or element including a web section, spaced 90 wing hinges angularly related to said web section and connected thereto, and a neck portion connecting said wing hinges and angularly related to said web section.

2. A vibratable member for transmitting energy impulses from one region to another, said member comprising a single shaped member of sheet material terminating at one end in a web section, spaced wing hinges 95 angularly related to said web section and connected thereto, and a neck portion connecting said wing hinges and angularly related to said web section. 100

3. A vibratable member for transmitting energy impulses from one region to another, 105 said member comprising a single shaped member of sheet material having a hollow, circumferentially complete portion substantially rectangular in cross-section, one wall of said hollow portion terminating in a web section, spaced wing hinges angularly related to said web section and connected thereto, and a neck portion connecting said wing 110 hinges and angularly related to said web section.

4. A vibratable member for transmitting energy impulses from one region to another, 115 said member comprising a single shaped member of sheet material having spaced walls connected by a transverse wall terminating in a web section, spaced wing hinges angularly related to said web section and connected thereto, and a neck portion connecting said wing hinges and angularly related to said web section. 120

5. A vibratable member for transmitting energy impulses from one region to another, 125 said member comprising a single shaped member of sheet material having spaced walls connected by a transverse wall, said 130

transverse wall terminating in a web section extending beyond each side thereof, spaced wing hinges disposed in a single plane substantially at right angles to said web section and formed integrally therewith, and a neck portion disposed in said plane and formed integrally with said web section and with said wing hinges.

6. A vibratable member comprising an elongated diaphragm-connecting-element, and a talking-machine stylus-retaining-element, one of said elements having a flange transversely disposed with respect to its longitudinal axis, and formed integrally therewith, and the other of said elements having a slot for the reception of said flange.

7. A vibratable member comprising an elongated diaphragm-connecting element, and a talking-machine-stylus-retaining-element, said first named element being formed from a single piece of sheet material and having spaced walls connected by a transverse wall terminating in a flanged web section, the end of said second named element being received between said walls and comprising a slot for the reception of the flange of said web section.

8. A vibratable member comprising an elongated diaphragm-connecting element, and a talking-machine-stylus-retaining-element, said first named element being shaped from a single piece of sheet material and having spaced walls connected by a transverse wall terminating in a web section having spaced wing hinges and a connecting neck angularly related with respect thereto, the end of said second named element being received between said walls and comprising a slot for the reception of said connecting neck.

9. A stylus arm or bar comprising a hollow member, laterally extending wings secured thereto, and a stylus holding member secured to said member and wings.

45 In testimony whereof I have signed this specification this 27th day of September, 1928.

FLORICEL A. STAPLER.
